UNITED STATES PATENT OFFICE.

ALVIN L. LEIBE, OF IRVINGTON, NEW JERSEY.

EYEGLASSES AND THE LIKE.

Application filed September 3, 1921. Serial No. 498,398.

To all whom it may concern:

Be it known that I, ALVIN L. LEIBE, a citizen of the United States, residing at Irvington, in the county of Essex and State of New Jersey, have invented certain new and useful Improvements in Eyeglasses and the like, of which the following is a specification.

The present invention appertains to improvements in eye-glasses or spectacles, and has particular reference to the manufacture of a novel form of connection intermediate the bridge and the lens supports as especially adapted for what are commonly known as folding oxfords.

To obtain a clear understanding of the objects of this invention, it may be stated at this point that it is at present customary in the manufacture of devices of this character to take a piece of spring stock for the bridge and connect thereto a knuckle piece or joint member either by soldering the same so as to make it integral or attaching the part by means of a screw. The eye-glass rim has then secured to it what is known in the trade as a "screw-hollow-wire", and this is usually cut through and provided with a screw by means of which the rim is opened and closed when inserting a lens and at one end of this part is soldered a spring receiving barrel to receive a coil spring for actuating the glass in unfolding. To this the bridge piece with its joint is connected in the usual way by a rivet pin and usually the parts are suitably washered as may be required.

This method of manufacture, almost universally followed, has a number of disadvantages, among which may be mentioned that in the first place the process of mounting of such small parts is delicate and tedious work and requires a number of operations, which makes for expense in assembling. Again, the bridge spring is necessarily foreshortened and this materially affects the resiliency or flexibility which is obtainable and reduces the life of the bridge spring.

It is the object of this invention to simplify materially the manufacture of these articles by so forming the bridge spring itself as to embody a spring container which is adapted to be connected with the joint member of a lens support whereby to obtain the benefit of increased length of the bridge

spring and essentially the flexibility of this part.

It is further an object to provide a single member or connection for the lens mounting to replace the ordinarily separate parts, that 60 for receiving the clamping screw and that which receives the actuating spring hereinbefore mentioned.

These and such other objects as may hereinafter appear are attained by the novel construction, combination and arrangement of parts to be hereinafter specifically described and claimed. Reference will now be had to the accompanying drawings forming a part of this specification wherein:

Figure 1 is a front elevation of a folding oxford constructed in accordance with my invention.

Figure 2 is a sectional view on the line 2—2 of Figure 1, considerably enlarged.

Figure 3 is an enlarged sectional view on the line 3—3 of Figure 2 showing more clearly the formation of the bridge spring extremity.

Figure 4 is a detail perspective view of 80 the end of the bridge spring.

Figure 5 is a bottom plan view of the connector piece for the lens support.

Throughout the following detailed description and on the several figures of the drawing, similar parts are referred to by like reference characters.

Referring to the drawings, 1 designates a lens rim or support of the conventional type. Upon the upper part of this is attached by 90 means of solder or otherwise the connector piece 2 shown most clearly in Figure 5 of the drawing. This part is formed of a small piece of sheet metal stamped or rolled into the form shown in the figure just mentioned and when attached the tubular extremity is sawed through, as indicated at the point 3, so as to form an opening by means of which the rim 1 is permitted to receive its glass. Into the separated extremity 2' at one side 100 of the opening a screw 4 is passed and this extends into the main part 2 so as to produce the necessary clamping action.

The bridge spring 5 has each of its extremities bent into the configuration shown 105 most clearly in Figures 3 and 4, so as to form a substantially cylindrical spring container 6 which, as will be observed, constitutes the receiver for the actuating spring 7, coiled about the pintle 8 which forms the 110

pivot connection between the bridge spring and the connector part or piece 2. One end of this coil spring passes out laterally through the side of the part 2 adjacent to the bore for the pintle as shown at 7', while the opposite end of the spring passes out through an opening in the end of the barrel part as indicated at 7".

It will be observed that in the bending up 10 or inwardly of the barrel part 6 a flattened surface is given to the spring as indicated at 9 which conforms to the configuration of the rim as shown in Figure 3. This special configuration is utilized to obtain a co-action 15 between the end of the spring and the rim which limits the pivotal or unfolding movement of the eye-glass or lens support.

It will thus be seen that without departing 20 from the conventional form of a folding oxford I have produced a simplification of the parts without sacrificing any of the strength which is required, but rather, on the other hand, obtaining a much more satisfactory connection or mounting than is obtainable with the known construction hereinbefore described. By the formation of the 25 bridge spring in the manner specified, benefit is obtained of the full length of the spring part up to the pintle, thus increasing the 30 flexibility of this element which is in a device of this character extremely important owing to the fact that there is a great amount of strain produced by folding one lens into position upon the other, as is customary in these devices.

Having thus described my invention, what I claim as new and desire to secure by Letters Patent is:

1. In a folding oxford, the combination 40 with a lens rim, of a connector piece attached thereto and having a bifurcated portion, a bridge spring having its extremity returned to provide a spring container adapted to be received within the bifurcated portion of the connector piece, said spring container having a portion which is adapted to co-act with the rim to form a limiting means restricting the pivotal movement of the rim with respect to the bridge spring, a pivot connection between the bridge spring and the connector piece, and a spring operatively mounted within the spring connector.

2. In a device of the class described, the combination of a connector member attached 55 thereto, a bridge spring having its extremity bent backwardly so as to form a spring container, the resiliency of the bridge spring being thus rendered effective to the end thereof, said container being adapted to be received by the connector member, a pintle 60 passing through the connector member and bridge spring, and spring means surround-

ing said pintle and seated in the barrel of the bridge spring.

3. In an optical device of the class 65 described, the combination with a glass rim, of a connector part attached thereto and having one end bifurcated to receive the end of a bridge spring, a bridge spring having its extremity turned inwardly to form a 70 spring container, the resiliency of the bridge spring being thus rendered effective up to the end thereof, and a pintle passing through the connector piece and the bridge spring container.

4. In a folding oxford, the combination with a lens rim of a connector piece attached thereto and provided with a cylinder bore at one end to receive a screw, said piece being bifurcated at its opposite end to receive a 80 bridge spring, a bridge spring having its extremity bent around to form a spring container adapted to be received by the connector piece as aforesaid, the extremity of said bridge spring being shaped to coact with 85 the rim to form a limiting means restricting the pivotal movement of the glass with respect to the bridge spring, and a pivot connection between the bridge spring and the connector piece.

5. In a folding oxford of the class described, the combination with a lens support of a connector piece formed of stamped metal rolled together at one end to provide a screw receiving bore, and bifurcated at its 95 opposite end to pivotally receive the bridge spring.

6. As a new article of manufacture, a flexible bridge spring strip for folding oxford 100 and the like having its extremities bent inwardly and around to form a substantially cylindrical spring container.

7. As a new article of manufacture, a flexible bridge spring strip for holding oxford 105 or the like having its extremities bent sharply inward and around to form a substantially cylindrical container and a flattened shoulder or surface adapted to coact with a glass frame for limiting the swinging movement of the latter.

8. In a folding oxford, the combination with a lens rim, of a connector piece attached thereto and having a bifurcated portion, a resilient bridge spring strip, having one end thereof returned to provide a spring 115 container adapted to be received within the bifurcated portion of the connector, the resiliency of the bridge spring being thus rendered effective to the end thereof, a pivot connection between the bridge spring and 120 the connector piece, and a spring operatively mounted within the spring container.

In testimony whereof I affix my signature.

ALVIN L. LEIBE.
